UNITED STATES PATENT OFFICE.

HERBERT B. KINGSLEY, OF JEWETT CITY, CONNECTICUT, ASSIGNOR OF TWO-FIFTHS
TO WILLIAM D. HILL, OF JEWETT CITY, CONNECTICUT.

DEVICE FOR REMOVING CONDENSATE.

1,413,480.

Specification of Letters Patent. Patented Apr. 18, 1922.

Application filed June 8, 1920. Serial No. 387,300.

To all whom it may concern:

Be it known that I, HERBERT B. KINGSLEY, a citizen of the United States, and a resident of Jewett City, in the county of 5 New London and State of Connecticut, have invented a new and Improved Device for Removing Condensate, of which the following is a full, clear, and exact description.

This invention relates to an improvement 10 in means for removing condensate or the water of condensation from the interior of a hollow body which is heated by live steam and is especially designed for use in connection with steam heated drying cylinders or drums.

The invention broadly contemplates a device of this character which automatically operates to intermittently remove the water of condensation formed in a steam heated 20 body whereby the same will be maintained practically free of condensate to provide for a maximum steam space therein.

An important object of the invention resides in the provision of means for controlling the outlet valve to effect removal of the water of condensation without permitting the escape of steam from the cylinder.

A further object of the invention resides in the provision of adjustable means for 30 limiting the opening of the valve to suit various conditions.

A still further object of the invention is to provide in combination with a device of the character described means for concentrating the water of condensation against the valve controlling means.

With the above recited and other objects and advantages in view, some of which will be more apparent as the nature, purpose 40 and operation of the device is understood from the following detailed description and claims, reference is had to the accompanying drawings forming a part of this application and in which—

45 Figure 1 is a transverse sectional view through a drying cylinder with the condensate removing device applied.

Figure 2 is a fragmentary longitudinal sectional view through the cylinder, taken 50 approximately on the line 2—2 of Fig. 1.

Figure 3 is an enlarged detail side elevation of the invention.

Figure 4 is a rear view thereof.

Figure 5 is a plan view of the same.

Referring to the drawings by characters of reference which denote like parts throughout the several views thereof, 10 designates a heating cylinder or drum of a revolving type which is provided with an inlet (not shown) for the admission of live steam thereto for heating the same. In practice the cylinder is associated with others of a similar kind over which material is threaded for drying the same.

The invention contemplates a means for removing the water of condensation formed by the steam in the cylinder without permitting of the escape of any of the steam.

The invention further contemplates a means for this character which is preferably automatic in its operation and the same will be set forth in detail hereafter. In the specific form of cylinder illustrated, the same is provided with a trunnion 11 having an axial bore 12 which constitutes an outlet therefrom, the inlet for the steam being arranged in a similar trunnion disposed at the opposite end.

An outlet pipe comprising the sections 13 and 14 connected by an elbow 15 is provided and the free extremity of the 80 section 13 is threaded axially and communicates with the bore 12 of the trunnion. The section 14 which is radially disposed from the axis of the cylinder 10 is provided at its free extremity with an outlet nozzle 16 pro-

85 vided with an arcuate bearing foot 17 which is designed to frictionally engage and bear against the inner periphery of the cylinder. The outlet nozzle is provided with an outlet opening 18 in the side wall thereof and 90 adjacent its outer extremity. A gate valve 19 is pivoted to the outlet nozzle at 20 adjacent the outlet opening 18 and functions to respectively close or open the same. The valve is provided with an angularly disposed 95 arm 21 which is connected by the link 22 to one extremity of the lever 23. The lever 23 is pivoted to the side of the outlet nozzle as at 24 and its opposite extremity is connected by link 25 to the blade 26 which is pivoted 100 as at 27 to the bearing lug 28 formed on the front face of the nozzle. The free extremity of a gooseneck 29 carried by the nozzle has secured thereto one extremity of the coil contractile spring 30, the opposite extremity of 105 which is connected to the blade adjacent its free end. By this arrangement the blade which is disposed transversely in front of

the nozzle is normally arranged parallel thereto under the action of the spring 30, the contact of the adjusting screw 31 with the lever serving to limit the movement of the 5 free end of the blade toward the gooseneck. The adjustments of the screw 31 are secured through its threaded engagement in the lug 32 cast or otherwise formed on the outlet nozzle. A binding nut 33 is threaded on the 10 screw to retain the same in its adjusted positions against accidental derangement. A similar screw 34 functions as a stop to limit the throw of the opposite arm of the lever 23, movement of the blade toward the outlet 15 nozzle and the consequent opening of the gate or valve 19.

In use and operation of the device in connection with a revolving cylinder which rotates in the direction indicated by the arrow 20 in Figure 1 of the drawings, when the blade 26 contacts with the condensate C which gravitates to the bottom of a cylinder, the impact of the water thereagainst will serve to swing the free end of the blade toward 25 the nozzle against the action of the spring 30. As the blade swings on the pivot 27 the link 25 will swing the lever 23 in a corresponding direction thereby exerting a thrust on the link 22 which will effect movement of 30 the gate 19 to uncover the outlet opening 18. The steam pressure within the cylinder being greater than the pressure in the outlet pipe will tend to force the condensate through the outlet pipe from the cylinder. 35 If desired a suitable pump may communicate with the outlet to create suction for withdrawing the condensate from the cylinder when the outlet is uncovered. In order to collect and concentrate the water of condensation against the blade, an angularly disposed rib 35 may be employed such as illustrated in Figures 1 and 2 of the drawings. By a device of the character described, it will be seen that the outlet opening is only 40 uncovered while the same is submerged in the water thus preventing the escape of steam for the reason that as soon as the blade is free from the water, the spring will operate to close the outlet opening. The 45 screw 34 is adjustable to vary the uncovering of the opening to suit various conditions. It is therefore seen that upon each revolution of the cylinder any water of condensation collected therein will be removed. 50

55 While the device is illustrated and described as particularly designed for use in connection with revolving cylinders, the same is capable of operation as well where the cylinder is stationary and the nozzle rotates within the same.

60 While there has been illustrated and described a single and preferred embodiment of the invention, no limitation is necessarily made to the precise structural details as it is 65 to be understood that modifications and

variations which fall within the scope of the appended claims may be resorted to when found expedient.

Having thus described my invention, I claim as new and desire to secure by Letters Patent:

1. In a steam heated cylinder, means movable through the condensate formed therein and operable by impact with the condensate for automatically removing therefrom the 75 water resulting from condensation of the steam.

2. In a steam heated cylinder, means movable through the condensate and operable by impact with the condensate for automatically and intermittently removing therefrom the water resulting from the condensation 80 of the steam.

3. In a steam heated cylinder, means arranged therein for automatically removing 85 therefrom the water resulting from condensation of the steam, said means being actuated by the impact of the means with the water upon movement of the same through 90 said water.

4. The combination with an interiorly steam heated cylinder having a normally closed outlet for the water of condensation, of means movable through said water and operable by impact therewith for effecting 95 the opening of said outlet to permit of the removal of said water from the cylinder.

5. The combination with an interiorly steam heated cylinder including a normally closed outlet for the water of condensation 100 formed therein, of means movable through said water having an outlet communicating with the cylinder outlet and a closure for the latter outlet operable by impact of the water therewith for effecting the opening of 105 said closure to permit of the removal of said water of condensation therefrom.

6. The combination with an interiorly steam heated cylindrical body having an outlet for the removal of the water formed 110 therein by condensation, of means normally closing said outlet, said means movable through the water of condensation for operating said means to effect the opening of 115 said closing means to permit of the removal of said water.

7. The combination with an interiorly steam heated cylinder provided with an outlet for the condensate, of an outlet pipe communicating with the outlet, and movable 120 through the condensate, a nozzle carried by the free extremity of the outlet pipe, a gate normally closing the outlet nozzle and means carried by the same and operable by impact with the condensate for opening said gate. 125

8. In an apparatus for effecting the removal of the water of condensation from the interior of a steam heated body having an outlet, a rotatable outlet pipe having a nozzle at its free extremity, said nozzle having 130

- an outlet opening, a gate normally closing the outlet opening, a blade pivoted to the nozzle in advance of the same, means connecting said blade with the gate, and means for normally holding the blade in a position to effect movement of the gate to cover the opening as and for the purpose specified. 5
9. In an apparatus for effecting the removal of the water of condensation from the interior of a steam heated body having an outlet, a rotatable outlet pipe having a nozzle at its free extremity, said nozzle having an outlet opening, a gate normally closing the outlet opening, a blade pivoted to the nozzle in advance of the same, means connecting said blade with the gate, means for normally holding the blade in a position to effect movement of the gate to cover the opening, and means for regulating the opening of the gate as and for the purpose specified. 10
10. In an apparatus for effecting the removal of the water of condensation from the interior of a steam heated body having an outlet, a rotatable outlet pipe having a nozzle at its free extremity, said nozzle having an outlet opening, a gate normally closing the outlet opening, a blade pivoted to the nozzle in advance of the same, means connecting said blade with the gate, means for normally holding the blade in a position to effect the movement of the gate to cover the opening as and for the purpose specified, and means arranged in said steam heated body for advancing the water of condensation into the presence of the blade. 15
11. The combination with interiorly steam heated cylinder provided with an outlet for the water of condensation of rotatable means communicating with said outlet for removing the water of condensation, said means being operable upon impact of the same with the water and during its passage through the same. 20
12. The combination with an interiorly steam heated cylinder provided with an outlet for water of condensation, of rotatable means communicating with said outlet for removing the water of condensation, said means being operable upon impact of the same with the water during its passage therethrough, and means arranged in said cylinder for advancing the water of condensation into the presence of the rotatable means. 25
13. In an apparatus for effecting the removal of water of condensation from the interior of a steam heated body having an outlet, a rotatable outlet pipe having a nozzle at its free extremity, said nozzle having an outlet opening, a gate normally closing the outlet opening, a blade pivoted to the nozzle in advance of the same, means connecting said blade with the gate, means normally holding the blade in a position to effect the movement of the gate to cover the opening as and for the purpose specified, and means arranged in said steam heated body for advancing the water of condensation into the presence of the blade. 30
14. In an apparatus for effecting the removal of water of condensation from the interior of a steam heated body having an outlet, a rotatable outlet pipe having a nozzle at its free extremity, said nozzle having an outlet opening, a gate normally closing the outlet opening, a blade pivoted to the nozzle in advance of the same, means connecting said blade with the gate, means normally holding the blade in a position to effect the movement of the gate to cover the opening as and for the purpose specified, and a spiral rib arranged in said steam heated body for advancing the water of condensation into the presence of the blade upon rotation of the cylinder. 35

HERBERT B. KINGSLEY.
